UNITED STATES PATENT OFFICE.

EDWARD W. CADY, OF MASON CITY, IOWA.

PITMAN.

SPECIFICATION forming part of Letters Patent No. 374,449, dated December 6, 1887.

Application filed December 18, 1886. Serial No. 221,994. (No model.)

To all whom it may concern:

Be it known that I, EDWARD W. CADY, a citizen of the United States, residing at Mason City, in the county of Cerro Gordo and State 5 of Iowa, have invented a new and useful Improvement in Pitman-Connecting Devices for Mowers, of which the following is a specification.

My invention relates to improvements in 10 pitman-connecting devices for mowers; and it consists in certain novel features hereinabove first fully described, and then pointed out in the claims.

In the accompanying drawings, which fully 15 illustrate my invention, Figure 1 is a perspective view of my improved device, and Fig. 2 is a central longitudinal vertical section of the same.

Referring to the drawings by letter, A designates the cutter-bar, and B the cutter-bar 20 head, secured thereto at one end. This cutter-bar head is composed of a triangular casting having open sides and having a longitudinal slot, C, in its rear edge, through which the 25 pitman passes. In the forward end of this triangular cutter-bar head I provide a coupling-block, E, which is secured adjustably within the same by the set-screw D, as shown. This set-screw D is inserted through and 30 works in the end of the cutter-bar head. Its end bears against the block E, so that by turning the said screw inward the block will be forced from the end of the cutter-bar head, thereby increasing the tension of the leaf- 35 springs, presently referred to. By turning the screw in the opposite direction the block will be free to move toward the front end of the cutter-bar head, thereby diminishing the tension of the springs.

40 E' E' designate two-leaf springs which have their forward ends secured to opposite sides of the coupling-block and their rear ends resting against the inner sides of the rear end walls of the casting or cutter-bar head on opposite sides of the slot C. The pitman E has its front end connected to the coupling-block E, and to the rear end of the said rod I secure the band or yoke G, which encircles the eccentric H on the driving-shaft I.

The operation of the device will be readily 50 understood. As the driving-shaft revolves, the eccentric causes the pitman to reciprocate and the said rod communicates its motion directly to the cutter-bar. In its forward movement the pitman acts directly against the 55 coupling-block, and thereby actuates the cutter-bar head, and in its backward movement it acts upon the springs E' to give the return-stroke to the said cutter-bar head. It will thus be seen that the springs serve to make the 60 strokes of the pitman smooth and even and also to overcome the effects of the change of stroke. It will also be seen that the rear part of the cutter-bar head serves as a guide for the pitman, which passes through the slot 65 therein, and the cutter-bar head serves also as a means for securing the cutter-bar.

My device is simple and efficient, and its advantages will be readily appreciated.

Having thus described my invention, what 70 I claim, and desire to secure by Letters Patent, is—

1. The combination of the cutter bar head having the slot C, and the pitman secured within the cutter-bar head and passing through 75 the slot C, and mechanism for reciprocating said pitman, substantially as set forth.

2. The combination of the cutter-bar head having the slot C, the pitman secured within the cutter-bar head and passing through the slot 80 C and having the yoke or band, the eccentric, and the driving shaft, substantially as specified.

3. The combination of the cutter-bar head, the coupling-block adjustably secured within 85 the cutter-bar head, the pitman connected to the coupling-block, the springs having one end secured to the coupling-block and their other ends resting against the rear end of the cutter-bar head, and mechanism for reciprocating the 90 pitman, substantially as set forth.

In testimony that I claim the foregoing as my own I have hereto affixed my signature in presence of two witnesses.

E. W. CADY.
